United States Patent Office

Des. 191,583
Patented Oct. 17, 1961

191,583

TELEVISION TABLE OR SIMILAR ARTICLE

Le Roy Goldman, Park Forest, Ill., assignor to Comfort Lines, Inc., Chicago, Ill., a corporation of Illinois

Filed Dec. 23, 1960, Ser. No. 63,326

Term of patent 14 years

(Cl. D33—14)

The dominant features of my design, reside in those portions shown in full lines on the drawing.

I claim:

The ornamental design for a television table or similar article, substantially as shown and described.
